[57] CLAIM

The ornamental design of the five-point shield for child car seat, as shown and described.

DESCRIPTION

FIG. 1 is a perspective view of a five-point shield for child car seat showing our new design;
FIG. 2 is a rear elevational view;
FIG. 3 is a top plan view;
FIG. 4 is a bottom plan view; and,
FIG. 5 is a right side elevational view thereof.
The left side view is a mirror image of the right side view.
